(57) **CLAIM**

The ornamental design for a welding hood nut, as shown and described.

DESCRIPTION

FIG. 1 is an environmental perspective view of a first embodiment of a welding hood nut showing my new design;

FIG. 2 is a front elevational view thereof;

FIG. 3 is a rear elevational view thereof;

FIG. 4 is a right side elevational view with the left side being a mirror image thereof;

FIG. 5 is a top plan view thereof;

FIG. 6 is a bottom view thereof;

FIG. 7 is an environmental perspective view of a second embodiment of a welding hood nut showing my new design;

FIG. 8 is a front elevational view thereof;

FIG. 9 is a rear elevational view thereof;

FIG. 10 is a right side elevational view with the left side being a mirror image thereof; and,

FIG. 11 is a top plan view with the bottom view being a mirror image thereof.

The broken line showing of the welding helmet in FIGS. 1 and 7 is for illustrative purposes only and forms no part of the claimed design.
